APPARATUS FOR BURNING PULVERIZED FUEL

Ollison Craig, Worcester, Mass., assignor to Riley Stoker Corporation, Worcester, Mass., a corporation of Massachusetts

Application July 13, 1931, Serial No. 550,494

7 Claims. (CL. 110—104)

This invention relates to the combustion of pulverized fuel, and more particularly to apparatus for pulverizing coal or a similar fuel and delivering it directly to a furnace for combustion therein.

Pulverized fuel is ordinarily delivered to a furnace burner by means of a current of primary air which travels at a constant velocity, and any additional or so-called secondary air necessary to complete the combustion of the fuel is supplied at the furnace, either through the burner or through ports in the furnace walls. If the demand for heat decreases, it is customary to reduce the quantity of fuel and the quantity of

secondary air. If the demand becomes still less, the secondary air may be entirely cut off, and the primary air alone depended upon to support combustion, the rate of fuel supply being reduced to the amount which can be burned by means

of the primary air. It will thus be seen that the amount of the primary air flow determines the minimum rate of heat release in the furnace. The primary air usually represents a substantial proportion, usually at least 15 or 20 per cent, of the total air supplied at the maximum rate of combustion. Hence the range of ratings over which such a furnace can be operated is seriously limited, and it is seldom practical to obtain a ratio of over 5 to 1 between the maximum and

minimum combustion rates, although in many installations a very much higher ratio is desired. During periods of low demand in such cases, it is customary to operate the furnace intermittently, which has many practical disadvantages. Such operation not only requires constant supervision on the part of the operators, but it also causes expansion difficulties in the furnace structure and associated parts due to the fluctuating temperatures.

Although it has been proposed heretofore to reduce the quantity of primary air as the demand for heat decreases, this decreases the velocity of the fuel and air mixture issuing from the burner nozzle and results in additional difficulties. It is found that if this velocity is made too low, the flame will strike back into the burner nozzle and cause destruction of the burner from over-heating. The rate of flame propagation varies with the percentages of volatile matter and ash in the fuel and with the relative proportions of fuel and air, but in the case of ordinary bituminous coal when burned in pulverized form it is seldom practical to operate with a primary air velocity at the burner nozzle of less than

2000 feet per minute. This therefore determines

the minimum rate of air flow and prevents further reduction in the combustion rate.

A still further difficulty is encountered in burning pulverized fuel at low combustion rates. The fuel as it enters the furnace must immediately 60 ignite, or the flame will become extinguished. This ignition is ordinarily obtained largely by means of heat radiated to the incoming fuel from the adjacent walls of the furnace. However, at low combustion rates the furnace temperature 65 decreases, and the heat radiated to the fuel decreases in a much greater ratio, thereby rendering it extremely difficult to operate under these conditions.

It is accordingly the main object of the invention to provide apparatus for burning pulverized fuel which will make possible operation over a wide range, and particularly to enable the rate of heat release to be reduced to a very low amount when the demand makes it desirable. 70

It is a further object of the invention to provide a pulverizing apparatus connected to supply pulverized fuel directly to a furnace for combustion, and so arranged that when the demand for heat is low it will supply a finer and hence 80 more easily ignited fuel supply.

It is a further object of the invention to provide a simple, convenient, and practical construction whereby the rate of flow of the primary air which transports the pulverized fuel from a 85 pulverizer to a furnace burner may be controlled as desired and whereby in particular it may be reduced in amount when the demand for heat decreases.

It is a further object of the invention to provide apparatus whereby the primary air flowing to a furnace may be reduced in amount, when the demand for heat is low, without decreasing the velocity of discharge into the furnace to a value below the rate of flame propagation. 90

It is a further object of the invention to provide a pulverizer connected to discharge pulverized fuel at will to either a large main burner or a small low capacity burner, and to provide control means whereby the quantity of primary air may be conveniently reduced when the small burner alone is in operation. 95

With these and other objects in view, as will be apparent to those skilled in the art, my invention resides in the combination of parts described 100 in the specification and covered by the claims appended hereto.

Referring to the drawing illustrating one embodiment of the invention, and in which like reference numerals indicate like parts:

Fig. 1 is a view of an apparatus arranged to deliver pulverized fuel to a furnace for combustion, certain parts being shown in section on the line 1—1 of Fig. 3;

5 Fig. 2 is a view of a portion of the apparatus shown in Fig. 1, with certain parts adjusted to different positions; and

10 Fig. 3 is an elevation of the pulverizing apparatus in a direction looking away from the furnace, the upper part of the casing being broken away for clearness of illustration.

15 In the drawing I have shown a pulverizing apparatus 10 of the general type disclosed in the patent to Andrews No. 1,763,496, which is particularly suitable for the pulverization of coal and similar fuels. Reference may be had to said patent for a detailed description of the pulverizer. This apparatus comprises a casing 11 shaped to provide a pulverizing chamber 12 and a 20 fan chamber 14 which communicate through an axial passage 15 forming a central outlet from the pulverizing chamber. An inlet chute 16 leads into the pulverizing chamber on the side opposite to the outlet 15, and provides a means 25 for introducing the coarse fuel to be pulverized. The upper wall of the chute 16 has an opening 18 therein for the admission of air, and an adjustable damper 19 is provided to control the rate of flow. The peripheral wall of the fan chamber 30 14 is shaped as a scroll or volute leading to a discharge opening 20.

35 A horizontal rotatable shaft 22 extends centrally through the casing 11 and supports a fan 23 in the fan chamber 14 and a vertical rotor disk 24 in the pulverizing chamber 12. Agitator pegs 26 are mounted on the inlet side of the disk 24, and pulverizing pegs 27 are mounted on the outlet side of the disk. These pegs 27 interfit with stationary pegs 28 mounted on the casing 40 wall. A series of preliminary breaker hammers 30 are arranged to revolve adjacent to the inlet 16, these hammers being carried by a small disk 31 mounted on the shaft 22. Radial rejector arms 32 are mounted on the shaft 22 and arranged 45 to revolve adjacent to the outlet 15.

50 In order to control the rate at which the coarse fuel is introduced into the pulverizing chamber 12, I provide a suitable feed regulating device. In the illustrated embodiment, this device comprises a rotatable star wheel 33 of well-known construction mounted within the upper portion of chute 16. The feeding rate may be varied by 55 adjusting the position of a plate 34 pivotally mounted on the chute adjacent to the wheel 33.

60 In operation, the shaft 22 is rotated at a high speed by a suitable source of power, such as an electric motor or steam turbine, and the fan 23 produces a powerful current of air through the pulverizing chamber 12 and outlet opening 15. Coarse fuel is delivered to the inlet chute 16 at a desired rate by means of the star wheel 33, and is broken up preliminarily by the hammers 30. The air current then carries the fuel around the periphery of the rotor disk and into contact with 65 the interfitting pegs 27 and 28, which reduce it to a finely pulverized condition. The fine fuel passes with the air current through the outlet 15 into the fan chamber 14, and is delivered to the discharge opening 20. Coarse particles in 70 the stream are caught by the rejector arms 32 and hurled back into the pulverizing chamber.

75 I have shown the pulverizing apparatus 10 arranged adjacent to a furnace having a refractory wall 35. A large main burner 36 is mounted upon the wall 35 and arranged to discharge fuel and air

80 into the furnace through a circular flaring opening 37 in the wall. The burner 36 comprises a central discharge nozzle 39 for the fuel and primary air, this nozzle being connected to the discharge 20 of the pulverizing apparatus by means of a pipe 40. Around the nozzle 39, a series of 85 guide vanes 41 are mounted to distribute and whirl the secondary air, which enters the furnace around the outside of the fuel stream. The secondary air is supplied to the burner 36 from an air duct 43, the rate of flow being regulatable by means of dampers 44. It will be understood that the duct 43 is supplied with air by a suitable fan (not shown). A suitable shut off valve 45 of the well known quarter turn plug type may be provided in the pipe 40.

90 In addition to the main burner 36, I preferably provide a small low capacity burner 47, which is mounted upon the wall 35 and arranged to discharge fuel and air into the furnace through a circular flaring opening 48 in the wall. This burner 47, as illustrated, is similar to the large burner, and comprises a central discharge nozzle 49 for the fuel and primary air, which is connected to the discharge 20 of the pulverizing apparatus 100 by means of a pipe 51. Around the nozzle 49, a series of guide vanes 52 are mounted to distribute and whirl the secondary air, which enters the furnace around the outside of the fuel stream. The secondary air is supplied to the burner 47 105 from the air duct 43, the rate of flow being regulatable by means of dampers 53. A shut off valve 54 is provided in the pipe 51.

110 It will now be seen that with the apparatus as so far described, the entire fuel and air stream 115 discharged by the fan 23 may be directed to either of the burners as desired. If burner 36 is to be operated, valve 45 will be opened and valve 54 closed. If burner 47 is to be operated, valve 54 will be opened and valve 45 closed. A supplementary switching valve 56 may be provided to prevent the pulverized fuel from piling up in a solid mass against either of the plug valves which may be closed. This supplementary valve 56 is shown as a flat plate pivotally mounted at one 120 edge about an axis located at the intersection of the adjacent edges of pipes 40 and 51. With burner 36 in operation, the valve 56 will be in the position illustrated in Fig. 1, while if burner 47 is to be operated, the valve will be raised to the 125 position shown in Fig. 2. It will be understood that an external handle (not shown) or similar device is provided whereby valve 56 may be adjusted and held in a desired position.

130 If now the entire fuel and air stream passing through the discharge opening 20 is directed to the low capacity burner 47, certain serious difficulties will arise. The burner nozzle 49 is much smaller than the nozzle 39, so that the resistance to the flow will be greatly increased and 135 the pressure at the fan outlet 20 will likewise increase to a very high value. This increased pressure will not only cause fine coal to be blown out from the pulverizer through clearance spaces and openings into the surrounding atmosphere, 140 but it will also greatly increase the velocity of flow through the nozzle 49. This discharge velocity will greatly exceed the rate of flame propagation and will result in blowing out the flame. At low rates of heat release, the furnace temperature is low, and it is necessary, if ignition 145 is to be maintained, that the velocity of fuel discharge shall only slightly exceed the rate of flame propagation. This enables the fuel to ignite close to the nozzle 49 and within the refractory 150

lined opening 48, so that the flame will maintain the surrounding refractories at a high temperature and the refractories in turn will radiate heat to the entering fuel stream.

- 5 If an attempt is made to reduce the velocity in burner nozzle 49 by partially closing valve 54, the undesirable back pressure will be still further increased. It has furthermore been found impractical to reduce the primary air flow by 80
 10 means of the air inlet damper 19, since there is a great deal of air leakage into the pulverizer past the coal feeding device. Moreover any reduction in the primary air flow obtained by throttling either the inlet or outlet of the pulverizer 85
 15 will reduce the air velocity through the pulverizing chamber and cause fuel to pile up in the bottom of the pulverizing chamber and drag against the rotor. Operation of the machine is thus rendered unsatisfactory. 90
 20 In order to overcome these difficulties I provide means whereby enough air is admitted to the pulverizing chamber not only to insure efficient circulation of the fuel but also to maintain the fuel in suspension where it may be 95
 25 struck by the impact beaters or revoluble pegs of the pulverizer and so be satisfactorily pulverized. I furthermore make possible satisfactory operation of both the furnace and the pulverizer at low rates of heat release. For this 100
 30 purpose I provide a by-pass conduit or pipe 58 through which a portion of the fuel and air discharged by the fan may be recirculated, preferably by returning it to the pulverizing chamber. This pipe 58, as illustrated, extends from the fan 105
 35 discharge opening 20 and is connected to the pulverizing chamber 12 on the inlet side of the disk 24 and near the shaft 22. A shut off valve 59, similar to valve 45, may be provided in the pipe 58. For the purpose of dividing the fuel 110
 40 stream in desired proportions between pipes 58 and 51, I preferably provide a valve 60, which is shown as a flat plate pivotally mounted at one edge about an axis located at the intersection of the adjacent edges of the pipes. This valve 45 may be adjusted manually by an external handle (not shown).

When it is desired to operate the furnace at high rates of heat release, valve 45 will be opened, valves 54 and 59 closed, and valves 56 and 60 will be adjusted to the positions shown in Fig. 1. All the air and pulverized fuel discharged by the fan 23 will therefore be delivered to the nozzle 39 of burner 36. Dampers 53 will be closed and dampers 44 opened to supply the secondary air needed to burn the fuel at the desired rate. As the demand for heat decreases, the fuel will be supplied to the chute 16 at a decreased rate and dampers 44 will be partially closed to decrease the secondary air supply. The point will eventually be reached at which the primary air supplied with the fuel through pipe 40 is sufficient to burn the fuel, and dampers 44 will then be completely closed. If the demand decreases still further, the fuel supply will be decreased accordingly, valve 59 will be opened, and valves 56 and 60 adjusted slightly upwardly to permit a portion of the fuel and air discharged by the fan to flow through the by-pass conduit 58 and thus back to the pulverizing chamber. This will decrease the quantity of primary air delivered to the burner nozzle 39 without increasing the back pressure at the fan discharge 20 or varying the air flow through the pulverizing chamber 12, and thus 75 the rate of heat release may be reduced.

The velocity of discharge at the nozzle 39 cannot be reduced below the rate of flame propagation, however, without causing the flame to strike back into the nozzle and thus overheat the burner. Hence, if the demand decreases still further, I open valve 54, close valve 45, and adjust valves 56 and 60 to the positions shown in Fig. 2, thus placing the low capacity burner 47 into operation. Valve 60 will be so positioned as to supply primary air to the nozzle 49 at a velocity slightly exceeding the rate of flame propagation, and dampers 53 will be adjusted to supply any secondary air necessary to burn the fuel at the desired rate. It will be apparent that by discharging the fuel into the furnace through the small nozzle 49 at low ratings instead of through the large nozzle 39 I have reduced the cross-sectional area of the jet of fuel and primary air, thereby permitting a considerable decrease in the quantity of primary air without reducing the discharge velocity below the rate of flame propagation. At the very lowest combustion rate, the dampers 53 will be entirely closed, and only the primary air from nozzle 49 will be depended upon to burn the fuel. It 100 will thus be seen that with a sufficiently small burner nozzle 49, any desired minimum combustion rate may be maintained continuously, with the limitation that sufficient heat must be released to make up for radiation losses through 105 the furnace walls and to maintain the refractories surrounding the opening 48 at a sufficiently high temperature to ignite the incoming fuel. The pipe 58 is shown of substantially the same size as pipe 40, so that it will be capable of 110 handling most of the air discharged by the fan when these low ratings are obtained.

It is a fact that the finer the pulverized fuel is ground, the easier it is to ignite in a furnace. Since at low ratings I re-circulate a large part of 115 the fuel through the pulverizing chamber and subject it for a second time to the action of the pulverizing elements, I am able to deliver a much finer product to the burner and can maintain ignition at much lower ratings. In the embodiment illustrated I am able to deliver an even finer product for combustion by segregating the coarser particles of fuel and returning them for further pulverization. Since these coarser particles are hurled outwardly in the fan chamber under the 125 influence of centrifugal force, I so arrange the by-pass conduit that it will directly receive these coarse particles as they move along the peripheral wall 65 of the fan chamber in approaching the discharge opening 20. The construction is shown 130 particularly in Fig. 2 in which the lower wall of the by-pass conduit 58 forms a continuation of the fan chamber peripheral wall 65. With this arrangement, the coarse particles will enter the by-pass conduit, while the fine particles will be 135 carried above the valve 60 by the air current and thus enter the pipe 51.

It will now be clear to those skilled in the art that I have provided a very simple apparatus whereby pulverized fuel may be burned in a furnace over an extremely wide range of ratings. By means of my invention, it is possible to operate a furnace fired by pulverized fuel at a very low rating continuously, and ready for operation at a high combustion rate upon a moment's notice. When the demand for heat is low, there is no necessity for operating the burners intermittently, as has been the practice heretofore, and constant supervision is not required.

Having thus described my invention, what I 150

claim as new and desire to secure by Letters Patent is:

1. A pulverized fuel burning system comprising walls forming a combustion chamber, walls forming a fan chamber, a rotatable fan within the fan chamber, means to deliver pulverized fuel and air to said fan chamber, a large furnace burner and a small furnace burner associated with the combustion chamber, means to conduct air and pulverized fuel from the fan chamber to said burners, means including a by-pass conduit to divert a portion of the air and fuel discharged by the fan and cause it to recirculate through the fan chamber, and valve means to control the relative velocities of flow to each of said burners and in said by-pass conduit. 10
2. A pulverized fuel burning system comprising walls forming a combustion chamber, walls forming a pulverizing chamber and a fan chamber which are connected by a passage forming an outlet from the pulverizing chamber, means in the pulverizing chamber to pulverize material, a rotatable fan mounted in the fan chamber, a large furnace burner and a small furnace burner associated with the combustion chamber, means to conduct air and pulverized fuel from the fan chamber to said burners, means including a by-pass conduit to divert a portion of the air and fuel discharged by the fan and cause it to recirculate through the pulverizing chamber and the fan chamber, and valve means to control the relative quantities of air and fuel flowing to the furnace and through the by-pass conduit. 20
3. A pulverized fuel burning system comprising a casing shaped to provide a pulverizing chamber and a fan chamber which are connected by a passage forming a central inlet to the fan chamber, a rotatable fan mounted in the fan chamber, means in the pulverizing chamber to pulverize material, the fan chamber having a discharge opening, a large furnace burner, a small furnace burner, pipes connecting the burners with the fan chamber discharge, a by-pass conduit connecting the fan chamber discharge with the pulverizing chamber, and valve means to control the relative velocities of flow in said pipes and conduit. 30
4. A pulverized fuel burning system comprising a casing shaped to provide a pulverizing chamber and a fan chamber which are connected by a passage forming a central inlet to the fan chamber, a rotatable fan mounted in the fan chamber, means in the pulverizing chamber to pulverize material, the fan chamber having a peripheral wall shaped as a scroll leading to a discharge opening, a large furnace burner, a small furnace burner, pipes connecting the burners with the fan chamber discharge, a by-pass conduit connecting the fan chamber discharge with the pulverizing chamber and positioned to receive coarse particles of fuel traveling along the

peripheral wall of the fan chamber, and valve means to control the relative velocities of flow in said pipes and conduit.

5. A pulverized fuel burning system comprising walls forming a pulverizing chamber and a fan chamber which are connected by a passage forming an outlet from the pulverizing chamber, means in the pulverizing chamber to pulverize material, a rotatable fan mounted in the fan chamber, walls forming a furnace chamber, means to conduct air and pulverized fuel from the fan chamber to the furnace chamber, means to vary the cross-sectional area available for the flow of the pulverized fuel and air into the furnace, means including a by-pass conduit to divert a portion of the fuel and air discharged by the fan and cause it to recirculate through the pulverizing chamber and the fan chamber, and valve means to control the relative quantities of air and fuel flowing to the furnace and through the by-pass conduit. 85

6. A pulverized fuel burning system comprising walls forming a combustion chamber, walls forming a fan chamber, a rotatable fan within the fan chamber, means to deliver pulverized fuel and air to said fan chamber, burner means arranged to project pulverized fuel and air into the combustion chamber, means to conduct air and pulverized fuel from the fan chamber to the burner means, means to vary the cross-sectional area available for the flow of the fuel and primary air into the combustion chamber, means including a by-pass conduit to divert a portion of the air and fuel discharged by the fan and cause it to recirculate through the fan chamber, and valve means to control the relative velocities of flow to the burner means and in said by-pass conduit. 100

7. A pulverized fuel burning system comprising a casing shaped to provide a pulverizing chamber having an outlet for fine fuel, means to introduce air and coarse fuel into the pulverizing chamber, a rotor mounted within the pulverizing chamber and provided with impact members arranged to pulverize the fuel as it is carried in suspension in air flowing through the pulverizing chamber, a fan chamber communicating with the outlet of the pulverizing chamber, a rotatable fan within the fan chamber arranged to withdraw fine fuel and air from the pulverizing chamber, a furnace burner, a pipe connecting the fan chamber with the burner, a by-pass conduit connecting the fan chamber with the pulverizing chamber, and valve means to control the relative velocities of flow in said pipe and by-pass conduit, whereby the air velocity in the pipe may be varied as desired while still maintaining a substantially constant air velocity through the pulverizing chamber to maintain the fuel in suspension therein. 115
